United States Patent Office

Des. 234,259
Patented Feb. 4, 1975

234,259

VASE OR SIMILAR ARTICLE

Arthur L. Harshman, Dunkirk, Ind., and James I. Messmer, Detroit, Mich., assignors to Indiana Glass Company, Dunkirk, Ind.

Filed Sept. 21, 1973, Ser. No. 399,366

Term of patent 14 years

Int. Cl. D11—02

U.S. Cl. D29—28 R

3-1 2

3-1 4

FIG. 1 is a side elevational view of a vase or similar article showing our new design.

FIG. 2 is a medial vertical sectional view.

FIG. 3 is a top plan view.

FIG. 4 is a horizontal sectional view taken along line 4-4 of FIG. 2.

The surface ornamentation extends around the entire circumference of the respective vase elements.

We claim:

The ornamental design for a vase or similar article, substantially as shown and described.
